UNITED STATES PATENT OFFICE.

RUDOLF KUSS, OF NEW YORK, N. Y., ASSIGNOR TO A. M. BOLLERMAN, INC., OF NEW YORK, N. Y., A CORPORATION OF NEW YORK.

AUTOMATIC MUSICAL INSTRUMENT.

1,318,773.

Specification of Letters Patent. Patented Oct. 14, 1919.

Application filed November 11, 1916. Serial No. 130,694.

To all whom it may concern:

Be it known that I, RUDOLF KUSS, a subject of the King of Germany, and resident of New York city, borough of Manhattan, in the county of New York and State of New York, have invented certain new and useful Improvements in Automatic Musical Instruments, of which the following is a specification.

10 My invention has particular reference to improvements in pneumatic player mechanisms for musical instruments, such as player pianos, objects of my invention being to provide simple and efficient means to enable accenting of the notes of compositions being played; to enable the perforated music sheet to be rapidly operated when desired, without production of musical tones, commonly called "skipping", and to enable 15 rapid rerolling of the music sheet.

My invention comprises novel details of improvement and combinations of parts that will be more fully hereinafter set forth and then pointed out in the claims.

25 Reference is to be had to the accompanying drawings forming part hereof, wherein,

Figure 1 is a front elevation illustrating an air chest equipped with my improvements;

30 Fig. 2 is a detail sectional plan view of the skipper valve mechanism, enlarged, the section being taken substantially on line 2, 2, in Fig. 1;

Fig. 3 is a cross sectional view of the 35 skipper valve substantially on the line 3, 3, in Fig. 2;

Fig. 4 is an enlarged sectional view of a portion of the player action controlling devices taken substantially on the line 4, 4, 40 in Fig. 1;

Fig. 5 is an enlarged sectional view of the motor controlling valves for "skipping" and for rerolling the perforated music sheet, the section being taken substantially on the line 45 5, 5, in Fig. 8;

Fig. 6 is an enlarged sectional plan illustrating tempo valve mechanism taken substantially on the line 6, 6, in Fig. 8;

Fig. 7 is an enlarged sectional view illustrating an air chamber in the main air chest for communication with a motor, the section being taken on the line 7, 7, in Fig. 5;

Fig. 8 is an enlarged elevation of one end

of the main air chest illustrating the tempo valve chest in section substantially on the line 8, 8, in Fig. 5, the bellows K being omitted;

Fig. 9 is a sectional plan view through the governor bellows substantially on the line 9, 9, in Fig. 8;

Fig. 10 is a face view of a portion of the front wall of the main air chest, hereinafter more particularly referred to;

Fig. 11 is an enlarged vertical section substantially on the line 11, 11, in Fig. 1, illustrating parts for controlling rewinding of the music sheet;

Fig. 12 is a section substantially on the line 12, 12, in Fig. 1, illustrating parts for controlling the playing mechanism;

Fig. 13 is a section substantially on the line 13, 13 in Fig. 1, illustrating means controlling the "skipping" operation.

Fig. 14 is an enlarged sectional view of the skipping valve, substantially on the line 14, 14, in Fig. 13;

Fig. 15 is a section substantially on the line 15, 15, in Fig. 1; and

Fig. 16 is a sectional detail through block L².

Similar numerals and letters of reference indicate corresponding parts in the several views.

In the accompanying drawings A indicates the main exhaust chest, pedals being indicated at B adapted to actuate pumping bellows C. Equalizing bellows D are in communication with chest A through port or ports 14. All of said parts may be arranged in any well known manner, and are adapted to be included in an automatic musical instrument. At one end of chest A I have shown a chambered block or secondary chest E, which may be secured in place by screws and provides a chamber 17 in communication with a channel or pipe 18 that is intended to communicate with the action chest of any suitable pneumatic player mechanism. At e is a recess in block E, a diaphragm or pouch 26 being shown secured to block E separating chamber 17 from recess e. A small bleed passage e² provides communication between recess e and chest A. A tube 16 is in communication at one end with chest A, being shown in communication with equalizing bellows D through port 16^a, 100

105

the bellows being in communication with chest A through one or more ports 14, the opposite end of tube 16 opposing diaphragm or movable member 26. Ordinary or normal playing may be carried out with the parts in such condition, but when it is desired to accent a note or notes, the operator may merely operate the pedal or pedals more rapidly or forcibly to cause suction through bleed e^2 to exhaust recess e and draw back diaphragm 26 from tube 16, to permit a greater volume of air then to be drawn from the action chest through tube 16 to increase the blows of the hammer on the strings of the piano.

To control the action of diaphragm 26, to stop the operation of the action, for purposes to be stated, I provide the following arrangements: A tube 25 communicates with recess e and also communicates with a channel 25^a formed in a chest F shown secured on chest A (Figs. 1 and 11). The interior of chest F is in communication with chest A through a passage 25^b (Fig. 11). A valve 24 normally closes the passage 24^a in a wall of chest F that communicates with channel 25^a. Valve 24^b on the stem 24^c and spaced from valve 24 on said stem normally opens the passage 24^a to the interior of chest F.

A recess f in a wall of chest F is covered by a diaphragm 23 and a bleed passage f^3 provides communication between the interior of chest F and recess f . Under normal conditions exhaust in chest A through passage 25^b keeps valve 24 closed, hence since pipe 25 is, through channel 25^a, normally in communication with the space f^2 in chest F and also in communication with the recess e , the exhaust in said chests and recess will be balanced so that the diaphragm 26 will be inactive and loose, and will permit the flow of air from the action chest through chamber 17 to tube 16, thence through equalizing bellows 15 to chest A.

I provide means to permit acceleration of the motor that drives the winding mechanism for the perforated music sheet, in order, when desired, not to play a portion of the composition, commonly called "skipping", and at such time to shut off or stop the operation of the action. For such purpose I provide means to cause diaphragm 26 to close against tube 16 and at the same time to operate devices to cause acceleration of the motor for skipping. To prevent operation of the action I provide the following devices: A tube 21 communicates through a channel f^4 with recess f (Fig. 11), which tube 21 leads to a channel 21^a in a block or chest G, (Figs. 1 and 2), to a port 20, normally closed by a valve 20^a, (Fig. 3). Said valve may be operated by a push button 19 to open port 20^a. When button 19 is pressed and valve 20^a opens, air entering channel 21^a will flow through pipe 21 and channel f^4 to recess f and cause movement of diaphragm 23 due to exhaust in chest A, which will operate stem 24^c and close valve 24^b while opening valve 24, whereupon air entering recess 25^a will flow through pipe 25 into recess e , permitting diaphragm 26 to be drawn against tube 16 to stop the operation of the action. At the time that air enters port 20, as above stated, pipe 22, that communicates with said port through channel 22^a, will receive air. Said pipe leads to a channel 22^b in a chest 29 (Figs. 1 and 13), said channel communicating with a recess 22^c shown in a wall of said chest, over which recess a diaphragm 27 is secured. A bleed 29^a provides communication between recess 22^c and the chamber 29^b of chest 29. Said chamber communicates through bleed 30 with chest A. At 28 is a valve shown adapted to operate in an opening in the wall of chest 29 opposing diaphragm 27, said valve being adapted normally to close a channel 31^a that communicates with pipe 31 (Fig. 14). Pipe 31 leads to a recess 31^b in a wall of a chest H that is shown secured on chest A. A diaphragm or movable member 32 covers recess 31^b and normally closes against a tube 33, shown passing through chest H and communicating with chest A. The motor for causing the music sheet to traverse the tracker in an ordinary manner is to be connected to a pipe I. Said pipe communicates with a chamber 13 at one end of chest A (Figs. 5, 6 and 7). Said chamber communicates through a port 12 with chest H (Fig. 6) shown secured upon chest A over a recess 10 in the front wall of chest A. Recess 10 is in communication through port or passage 11 with chest H (Fig. 6), said port or passage being controlled by valve 11^a to be operated by rod 11^b for controlling the speed of the motor in any well known manner. The equalizing bellows K communicates with chest A through passage 8 and with recess 10 through port 9 (Fig. 9), the normal motor operating exhaust being from pipe I through chamber 13, port 12, chest H, port 11, recess 10, port 9, equalizer K, and passage 8 to exhaust chest A. When "skipping" is desired, the valve or button 19 will be operated, to cause opening of port 20, to stop the operation of the action as before explained, and when air enters pipe 22 and flows into recess 22^c, the exhaust from chamber 29^b and channel 30 to chest A will cause valve 28 to move and place pipe 31 through channel 31^a into communication with chamber 29^b, and exhaust is then effected through pipe 31, whereupon diaphragm 32 will be drawn away from tube 33 and thus direct communication from chest A through chest H to pipe I and thence to the motor will be opened, (regardless of the position of valve 11^a), whereupon the speeding up of the motor will be accelerated to 130

cause the perforated music sheet to be drawn more rapidly across the tracker. To stop the "skipping" action and again cause playing of the composition, button 19 is released, 5 whereupon valve 20^a closes, exhaust through pipes 21 and 22 is shut off, valves 24 and 24^b will return to their normal positions (Fig. 11), permitting the release of diaphragm 26 from tube 16, and valve 28 will 10 cause shutting off exhaust from pipe 31 and recess 31^b, whereupon exhaust through tube 33 will again draw diaphragm 32 against the latter, and the motor will continue to operate under usual conditions.

15 I also provide means for causing operation of the motor for rewinding or rerolling the perforated music sheet, and at such time to stop the operation of the action through the operation of diaphragm 26 for 20 closing tube 16 in the manner described with respect to the same for "skipping". The chest F' is provided with a passage 1^a normally open to atmosphere by reason of the normally open condition of valve 1 (Figs. 25 1 and 12). Said valve is shown provided with a stem 1^b having a valve 1^c normally closing passage 1^a. A diaphragm 1^d normally acts against stem 1^b to keep valve 1^c closed, said diaphragm being shown over a 30 recess 1^e in a wall of the chest F'. A bleed 3 provides communication between chest F' and recess 1^e. A pipe 2 provides communication between chests A and F'. A tube 4 communicates with recess 1^e through channel 4^a (Fig. 12), and said tube communicates with a passage 4^b in a block L shown secured on chest A. Said passage 4^b is normally open, and is adapted to be closed by a valve 5 (Figs. 1 and 15). One arm of a lever 34 35 is connected with stem 5^a of valve 5, and the opposite arm of said lever is adapted to operate a valve stem 35^a and valve indicated at 35 in a block L² (see Fig. 16), similar to that illustrated in Fig. 15, valve 35, however, 40 being normally closed. A tube 37 communicates with the passage 37^a in block L² (Fig. 16) corresponding to passage 4^b of block L, and leads to and communicates with recess f of chest F (Fig. 11), for a purpose 45 similar to that of pipe 21. A pipe 6 communicates through channel 6^a with passage 1^a (Fig. 12), being thus normally open to atmosphere, and at its opposite end pipe 6 is in communication with a recess 7^a in a wall 50 of chest H (Fig. 5). A diaphragm 7 covers said recess and opposes a tube 39 that communicates with chest H and with chest A. Since air normally enters pipe 6 and thence passes under diaphragm 7, exhaust in chest 55 60 A normally will cause diaphragm 7 to close tube 39, so that normal flow of air from the motor to chest A will be through the chamber 13 and ports previously described controlled by valve 11^a. When it is desired to 65 reroll the music sheet the lever 34 will be

swung to the right (Fig. 1), thereby closing valve 5 and opening valve 35. The closing of valve 5 shuts off atmosphere from pipe 4, whereupon diaphragm 1^d will be drawn away from valve stem 1^b by reason of exhaust in the recess 1^e through bleed 3 into chest F' and valve 1 will close, valve 1^c thereupon opening communication from chest F' through passage 6^a and pipe 6 to recess 7^a. Exhaust from chamber 7^a through pipe 6, chest F', and thence to chest A will cause diaphragm 7 to be drawn away from tube 39, whereupon full exhaust through said tube from the motor to chest A will be caused for acceleration of the speed of the 70 motor for rerolling the music sheet, it being understood that any reverse gearing of the rerolling mechanism will be operated in a well known manner. A rod 40 (Fig. 1) connected with lever 34 may be connected with 75 the reverse mechanism for operating the latter at the time that lever 34 is moved to cause operation of valves 5 and 35, so that the mechanism will be set for rerolling at the time that diaphragm 7 is drawn away 80 from tube 39. It will be understood that when lever 34 is moved, causing opening of valve 35, as before stated, air will flow through tube 37 to recess f, of chest F, thereby permitting exhaust in chest F to 85 cause diaphragm 23 to operate valves 24 and 24^b to shut off exhaust from pipe 25 and admit air thereto, whereby exhaust in chest A will draw diaphragm 26 against tube 16 to 90 shut off exhaust from the action to stop 100 the latter, in manner before described, during rerolling of the music sheet.

While I have described diaphragm 26, tube 16 and bleed e² as adapted for use for accenting desired portions of a musical composition being rendered, merely by increasing the pumping operation at the time desired, and have also described said diaphragm and tube as co-operative for stopping the operation of the action when "skipping" or "rerolling" is desired, by allowing air to enter the recess e for the last two named operations, it will be understood that said diaphragm, tube and bleed may be used only for accenting, which would be accomplished 105 by not connecting pipe 25 thereto. In other words, diaphragm 26, tube 16 and bleed e², may be used with or without skipping or rerolling mechanisms, or both, the arrangements I have shown, therefor, being simple 110 and convenient for stopping the operation of the action when skipping or rerolling is to be effected.

Having now described my invention what I claim is:—

1. The combination of an exhaust chest, a secondary chest provided with a recess, a diaphragm over said recess, a bleed providing communication between said recess and the first named chest, said chests having a 130

passage providing communication between said chests and opposed to said diaphragm, and means to provide communication between said secondary chest and the action chest.

2. The combination of an exhaust chest, an equalizing bellows communicating therewith, a secondary chest, a tube providing communication between the last named chest and said bellows, the secondary chest having a recess opposing the tube, a diaphragm over said recess to coact with said tube, a bleed providing communication between the first named chest and said recess, and means to provide communication between the secondary chest and an action chest.

3. The combination of an exhaust chest, a secondary chest, a passage providing communication therebetween, a movable member to control said passage, a bleed providing communication between the first named chest and a space opposing said movable member, means to provide communication between the secondary chest and an action chest, a tube communicating with said space, means normally providing communication between said tube and the first named chest, and means to at will shut off such communication and admit air to said tube to cause the diaphragm to shut off air from said passage.

4. The combination of an exhaust chest, a secondary chest, a passage providing communication therebetween, a movable member to control said passage, a bleed providing communication between the first named chest and a space opposing said movable member, means to provide communication between the secondary chest and an action chest, a tube communicating with said space, a third chest in communication with the first named chest, said tube being in normal communication with the third chest, valves to close communication between the last named chest and said tube and open communication from said tube to atmosphere, and means to at will cause operation of said valves.

5. The combination of an exhaust chest, a secondary chest in normal working communication therewith and adapted for communication with an action chest, a movable member to control exhaust from the secondary to the first named chest, a bleed providing normal exhaust on one side of said member, whereby increased exhaust on said side of said member will cause it to increase the communication between the exhaust and secondary chests to cause increase of exhaust in the action chest, a tube in communication with a space on one side of said member, valve-means normally closing said tube to atmosphere and placing said tube in communication with the exhaust chest, and means controllable at will to shut off com-

munication between said tube and the exhaust chest and to open said tube to atmosphere.

6. The combination of an exhaust chest, a secondary chest in normal working communication therewith and adapted for communication with an action chest, a movable member to control exhaust from the secondary to the first named chest, a bleed providing normal exhaust on one side of said member, whereby increased exhaust on said side of said member will cause it to increase the communication between the exhaust and secondary chests to cause increase of exhaust in the action chest, a tube in communication with a space on one side of said member, valve-means normally closing said tube to atmosphere and placing said tube in communication with the exhaust chest, means controllable at will to shut off communication between said tube and the exhaust chest and to open said tube to atmosphere, a third chest adapted for communication with a motor and normally in communication through a passage with the exhaust chest, an additional passage to control communication between the third chest and the exhaust chest, a movable member to control the last named passage, and means controlled by the operation of the third named means to cause said movable member to open communication between said passage and said third chest and the exhaust chest.

7. The combination of an exhaust chest, a secondary chest, a passage providing communication therebetween, a movable member to control said passage, a bleed providing communication between the first named chest and a space opposing said movable member, means to provide communication between the secondary chest and an action chest, a tube communicating with said space, means normally providing communication through said tube to the first named chest, means to at will shut off such communication and admit air to said tube to cause the diaphragm to shut off air from said passage, another chest in normal communication with the first named chest and adapted for communication with a motor, a tube providing communication between the last and first named chests, a movable member to control the flow from said other chest to the first named chest, said chest having a recess opposing said member, a tube communicating with said recess, a valve normally closing said tube, and means controlled by said second named means to cause admission of air to said recess when air is admitted to the first named movable member.

8. The combination of an exhaust chest, a secondary chest, a passage providing communication therebetween, a movable mem-

ber to control said passage, a bleed providing communication between the first named chest and a space opposing said movable member, means to provide communication between the secondary chest and an action chest, a tube communicating with said space, means normally providing communication through said tube to the first named chest, means to at will shut off such communication and admit air to said tube to cause the diaphragm to shut off air from said passage, another chest in normal communication with the first named chest and adapted for communication with a motor, a tube providing communication between the first and last named chests, the last named chest having a recess, a diaphragm over the recess opposing said tube, a tube communicating with said recess, a valve to control said tube, a fourth chest, a bleed providing communication between the first and last named chests, a diaphragm to operate said valve, the last named chest having a recess opposed to the diaphragm, and a tube in communication with said recess and with the second named means for controlling the flow of air for operating the last named diaphragm and valve.

9. The combination of an exhaust chest, a secondary chest, a passage providing communication therebetween, a movable member to control said passage, a bleed providing communication between the first named chest and a space opposing said movable member, means to provide communication between the secondary chest and an action

chest, a tube communicating with said space, means normally providing communication through said tube to the first named chest, means to at will shut off such communication and admit air to said tube to cause the movable member to shut off air from said passage, another chest in normal communication with the first named chest and adapted for communication with a motor, a tube providing communication between the first and last named chests, the last named chest having a recess, a diaphragm over the recess opposing said tube, a tube communicating with said recess, a chest F' in communication with the first named chest, the last named tube being connected to said chest F', a valve normally admitting air to said tube and a valve normally closing communication between chest F' and said tube, a diaphragm opposing said valve, said chest F' having a recess opposing the diaphragm, a bleed connecting said chest with said recess, a tube 4 communicating with said recess, a normally open valve to control said tube, a tube 37 communicating with the third named means, means normally closing communication to said tube, and means to open communication to said tube and close communication to the tube 4.

Signed at New York city, in the county of New York, and State of New York, this 4th day of October, A. D. 1916.
